VISUAL LANDING AID FOR AIRPLANES
Reginald F. Mitchell, 1329 Park Drive, Apt. 2,
Mountain View, Calif.
Filed Mar. 26, 1962, Ser. No. 182,236
5 Claims. (Cl. 340—26)

A number of large airports in this country are being equipped with a visual landing aid system, described below, which is most effective, but large, cumbersome and relatively expensive, and thus suitable only for the large airports.

It is the prime purpose of this invention to provide a small, compact and relatively low cost device which is suitable for the smallest airports, and for medium sized ones as well, which will give an approaching pilot the same (or essentially the same) appearing signals as the large airport system.

It is also a purpose of this invention to provide alternate means of design and construction of my device to permit such signal simulation to be obtained for different size and power of the lamps used, and whether single lamps or lamp banks are employed. Other features are covered in the specification.

FIG. 1 represents a schematic side view of the prior art R.A.E. system.

FIG. 2 is a diagrammatic representation of one arrangement of my device.

FIG. 3 shows one form of pink-red filter.

FIG. 4 shows another type of pink-red filter.

FIG. 5 shows another type of pink-red filter.

FIG. 6 shows a front view of the device with two vertical masks arranged to simulate the three-unit signal of the prior art R.A.E. system.

FIG. 7 shows one form of two zone shutter.

FIG. 8 shows how two large sized lamps can be set to give two images appearing relatively close together.

FIG. 9 shows another two lamp unit arrangement.

FIG. 10 shows still another two lamp arrangement, and also how two separate sections can be combined to give extra angular coverage.

The complete prior art R.A.E. (Royal Aircraft Establishment) system is described in a publication of the Federal Aviation Authority from which the following is quoted:

"The system developed at the Royal Aircraft Establishment (in England) and known as the RAE Angle of Approach Indicator (AAI) consists of 12 light source units arranged in bars, with three units placed on each side of the runway, opposite the 750 ft. mark (from the Threshold) and three on each side of the runway at the 1,250 ft. mark. Each unit is 4 ft. 6 inches square, and contains three high intensity sealed sealed-beam headlights, and three filters, the upper half of which is red and the lower half clear, mounted immediately in front of the lamps. A horizontal slit across the front of the box, about 2 inches wide, is at the focus of the lamps. The effect, then, is somewhat like a pinhole camera, so that an observer viewing the slit from a high angle sees white light. As his viewpoint is lowered, the light changes in color through pink to red. By adjusting the tilt of the box so that the bottom of the white beam is at the desired glide slope angle, the arrangement of all the units then will define a safe glide path corridor. When on the proper glide path, the pilot is in effect over-shooting the bars nearer the threshold, and undershooting the bars farther down. Thus, he will see the nearer bars as white and the farther bars as red. A position below the glide path will cause both bars to be red, and a high position will cause both rows of light to be white. Impending departure from the glide path is indicated to the pilot by a transition in color from red through pink to white or

2

vice versa. A movement to the high side will cause the farther bars to change from red through pink to white. A descent below the glide path will change the nearer bars from white through pink to red."

FIG. 1 represents a side view of a runway 1 where the rear prior art R.A.E. units would be set either side of the runway at a position 3, the near units at either side at a position 4, where the plane is intended to touch down at a position 2. The rear units at 3 project a composite beam which is white between the boundaries 5 and 6, and red between the boundaries 6 and 7. Between these zones, there is a narrow pink band along the boundary 6, caused by the blending of the red and white components of the composite beam. Similarly, the front units at 4 project a similarly composite beam which is white between the boundaries 8 and 9, red below 9, and pink along 9. Thus a pilot changing from positions 11, through 12, 13, 14, 15 to 16, will see two beams where the rear unit (top beam)/ front unit (low beam) will be respectively white/white; pink/white; red/white; red/pink and red/red.

FIG. 2 illustrates diagrammatically the basic parts in one type of my device. As with the other figures, this is extended vertically and compressed horizontally to show all essentials conveniently. The virtual images described below, for instance, are usually set a hundred feet or more back of the device. A light tight case 27 has two lamps 25 and 26 set one above the center line 35 of the unit, and one below it. A lens 20 is set at the other end of the case so that virtual images of the two lamp filaments 21 and 22 are at positions 30 and 33 respectively. Due to the comparatively great distance these images are back of the device, with the unit set at a glide slope angle 34 to the ground 1A, these two virtual images appear to come from positions 3A and 4A respectively and thus simulate the positions at which the actual images occur in FIG. 1. In order to get a similar effect to the "pinhole slit" of one lamp unit of the prior art RAE system, the filaments 21 and 22 should be of the line type set horizontally with respect to the center line 35 and parallel to both the center line and to the plane of the lens 20. To further simulate the RAE effect of three units set side by side, three line filament lamps could be set side by side with their filaments in line horizontally and all parallel to the said center line and said lens. In all mentions below, the term "lamp unit" is intended to cover either a single line filament lamp, three (or more or less) lamps set side by side, and also one or more long straight gas discharge type tubes of the stroboscopic variety, such as will be discussed in detail later. In practice, the lamps will be set a distance above and below the center line 35 such that the lens will form the virtual images 30 and 33 at an angular subtense that will enable the effect of their being at 3A and 4A, as covered above, to simulate the effect of a pilot seeing the RAE system as described. In front of the lamp unit 25 is a combination filter arranged so that a beam through its top portion 39 will give to a pilot at a position 12A the same pink image he would get from the rear unit at a position 12 in FIG. 1. Above this position, at 11A for example, the image of the top lamp unit will be white. Below the position 12A, the image of the top lamp unit will be red due to the light from the filament 21 passing through the lower portion 38 of the filter which is red. A similar filter 40 is set in front of the lower lamp unit 26 so that an observer at 15A will see a pink image of the filament 22, a white image if above the position 15A and a red image below 15A. Alternately, the lower filter could be set at 42 if preferred. It is apparent to those skilled in the art, from a consideration of FIGS. 1 and 2, and the foregoing descriptions, that my device placed at a position

approximately equivalent to 2 in FIG. 1, and at the side of a runway 1A, can simulate effectively the visual signal of one lamp unit of the RAE system set at 3 and one set at 4. One of my units set each side of the runway 1A, could then simulate the RAE system if lamps with line filaments, or three flash tube type lamps were used at positions 21 and 22, FIG. 8.

A few more or less obvious variations of my basic parts could be used without departing from the spirit and intention of my invention. For example, if the filter 38 had a bevelled top part 17, as in FIG. 3, the pink zones 12 and 15 would vary gradually from red to white. If notches were used as at 18 in FIG. 4, the pink zones would be of an even color throughout, the actual color would depend on the red density of the filter and the relative areas of the red and clear parts of the portion 18. If wavy type notches, such as 19 in FIG. 5 were used, the pink zones would vary from red to white somewhat like from the arrangement of FIG. 3. Any of these alternatives would perhaps be simpler than making a composite red-pink filter by using two different colors at 38 and 39.

If only one lamp is used at each position 25 and 26, using a long line type filament or a long flash tube arrangement, the effect of three side by side RAE lamp units can be simulated by using two vertical masks 23 and 24, as in FIG. 6. These could be placed at any convenient position in front of the lamps, but most conveniently are set adjacent to the lens. As shown, they are set vertically and divide the images of the filaments 21 and 22 into three side by side portions as shown in FIG. 6. Such arrangements permit simulating the RAE system whether one lamp unit is used or more than one at each position 25 and 26 respectively.

For small airport use, where cost, size and power may be a limiting factor, it may be helpful to increase the distance at which the signals can be recognized. This is most effectively done by flashing the images 30 and 33 at different rates—one slowly and one a bit faster. Rates of 2 to 4 per second for one and 8-12 for the other provide adequate signal recognition separation. Such flashing can most conveniently be done by using long stroboscopic tubular type lamps at 25 and 26, as explained above. If constant light lamps, such as incandescent filament lamps are used, then some form of alternating or rotating shutter can be used. Rather than use one in front of each lamp unit, it is more convenient to use a compound shutter such as shown in FIG. 7. The driving shaft 45 could be set off-axis as shown in FIG. 2, and the shutter driven in any way convenient, such as by a pulley 46. One zone 44 would be in front of the lower lamp 26, and the inner zone 43 would be in front of the top lamp 25. FIG. 7 shows large opaque blades 44 of the shutter having one clear segment 46 in each blade, and with a small opaque blade 47 in each of the inner zones 43. More could be used, or either parts 46 or 47 could be omitted as found convenient or desirable. Some variation of use of compound zone shutters warrant brief mention. If separate shutters were used in front of each lamp unit 25 and 26, the white segment 11A of the top lamp could be flashed at one rate by one shutter zone and its red segment (13A) at another rate. Then the white segment (14A) of the lower lamp 26 could be flashed at a different rate to 11A, and the lower red segment at a still different rate. Thus the different zones could readily be flash discriminated even if they could not be distinguished clearly. By using a 3-zone shutter in front of each lamp, the pink zones could be differentiated from all the other zones. Another approach would be to use a 4-zone shutter set off-center as at 45 in FIG. 2, with two zones interrupting the top beams and two other zones interrupting the lower beams. Using long flash tube type of lamps as suggested above would flash the top and bottom lamps differently but could not dif-

ferentially flash the colored zones. In this respect, a shutter interrupting the light from steadily burning lamps has advantages. For clarity, and because the actual means used are not part of this invention, such auxiliary units as motors, lamp flashing electrical equipment, cam operated switches etc., are not shown or described. Obvious alternative means of flash coding the light beams could be used without departing from the intent of this invention.

If relatively powerful lamps were to be used in my device, there may not be enough room to get them close enough together for the images 30 and 33 to appear to be at the proper relative angle to each other or to simulate the effect of their being from positions 2A and 4A as described. One obvious way to accomplish this is to separate the lamps an adequate physical distance, such as at 25 and 26 in FIGS. 8 and 9, and to use mirrors 50 and 53, or 56 and 57 to direct the beams along the paths 28/36 and 31/37 of the top and bottom lamps 25 and 26 of FIG. 2, so that the virtual images would still appear to come from 3A and 4A as before. In FIG. 8, the lamps 25 and 26 could illuminate apertures 49 and 52 which preferably but not necessarily could be of the slit type to give the long line type images desired. Such apertures could have condenser lenses 48 and 51 if desired or needed, or the apertures 49 and 51 could be omitted and the lenses 48 and 51 used to image the filaments 21 and 22 at or adjacent to the mirrors 50 and 53 so that these secondary image points would give the same effect as if the filaments were at 21 and 22 in FIG. 2. If curved mirrors were used as at 56 and 57 in FIG. 9, the physical arrangement could be simpler and the distance between lamps and the lens 20 shortened. With either of these arrangements, baffles 54 and 55 would be needed to prevent direct light from the lamp from reaching the lens 20. The mirrors 56 and 57 could be straight or curved as shown, but preferably would be cylindrical to preserve the line type images desired. Filters could be set at any convenient position such as at 38 to act the same as the equivalent filters in FIG. 2. Thus, either of these arrangements would perform the same as the arrangement in FIG. 2.

The lower section 64 in FIG. 10 shows one way in which one lamp could be arranged to give the same effect as two lamps 25 and 26 in FIG. 2. The lamp 56 would be set so that its filament 57 would be at the same position as the filament 21 in FIG. 2. A lens 58 could then focus an image of the filament 57 at a position 62 (on or adjacent to a mirror 61), which position 62 would correspond to the position 22 in FIG. 2. An optional aperture plate 59, with a slit 60 in it could be used if preferred. With light coming from the positions 57 and 62, and with filters 38 and 40 in similar positions to those in FIG. 2, it is apparent that the lower segment 64 will function exactly as the arrangement in FIG. 2. Other arrangements with only one lamp are obvious to those skilled in the art and can be used as long as they perform as explained. For example, in the top segment 63 in FIG. 10, the lamp could be set on axis at 66, and mirrors used at positions 21 and 22, with or without condensers, curved mirrors, apertures as might be found convenient. The arrangement shown for segment 63 in FIG. 10 is given to demonstrate how to differently arranged segments could be combined to give extra vertical coverage. In such a case, the lower segment 64 would function exactly as the arrangement in FIG. 2 with its top beam limited to a position 11A. The segment 63 could project two clear (white) beams to sections of the sky above the position 11A so that high flying planes could see such signals in ample time before reducing altitude. One important requirement for such a combination unit is that the virtual images of both lamps 21 and 57 must appear at a position 30, and both virtual images of lamps 22 and 62 must appear to come from a posi-

tion 33 so that as the pilot reduces altitude he would get the effect of "lines of light" coming from 3A and 4A at all times. Obviously, any of the other arrangements shown and described could be substituted for the segments 63 or 64 as long as they were set as just covered. Again, it may be desirable to extend the images in a horizontal azimuth without distortion. One very convenient way to do this is to set an external beam spreading lens unit 65. This could be a single cylindrical lens set with its cylindrical axis vertically, or a number of cylindrical lenses, or parts of cylindrical lenses combined as known in the art as lenticular lenses, could be set at 65 to perform a lateral beam spreading function. Here also, such a beam spreading arrangement could be used with any of the other arrangements shown and described. The one governing factor in the decision as to what arrangement or arrangements to use would be governed by the necessity of the final images appearing to emanate from positions 3A and 4A, and those images would give at least a recognizable or reasonable simulation of the equivalent signals from the prior art RAE type units as coming from positions 2 and 4 in FIG. 1. With these qualifications, one of my units set each side of a runway will enable a small airport to guide planes to a safe landing by projecting signals substantially similar to what a pilot familiar with said RAE system would know and recognize. Also, if cost were a factor, one of my units set at one side of said runway could simulate the signals of one side of an RAE system and would be adequate, or at least better than nothing.

I claim:

1. An airplane visual landing aid device consisting of an essentially light tight case containing a lens at one end and two lamp units at the other, said lamp units consisting of line filament type lamps arranged horizontally and parallel to said lens and also parallel to the optical axis of said device, one said lamp unit being set below said axis and one lamp unit above said axis, with both being set inside the normal focal point of said lens so that two virtual images appearing as lines of light will be formed a substantial distance back of said device, with said optical axis set at an angle to the runway equivalent to the desired glide slope approach angle, with special color filters set between said lamp units and said lens in such a way that a pilot approaching for a landing at too high an altitude will see said virtual images as two clear white lines of light one above the other, when at correct glide slope angle will see the top image colored red and the bottom image still clear, when at too low an altitude will see both images colored red, and when at positions intermediate between said high, correct and low positions will see a pink image of one of said lamp units, said device being set at one side of said runway.

2. An airplane visual landing aid device consisting of an essentially light tight case containing a lens at one end and two lamp units at the other end, said lamp units consisting of line filament type lamps arranged horizontally and parallel to said lens and also to the optical axis of said device, one said lamp unit being set below said axis and one above said axis, with mirrors set between said lamp units and said lens, with baffles to prevent direct light from lamp units reaching lens except via said mirrors, with one mirror above said axis and one below said axis, said lamp and mirror combinations being set so the said lamp filaments will be inside the normal focal point of said lens and such that two virtual images appearing as lines of light will be formed a substantial distance back of said device, with said optical axis set at an angle to the runway equivalent to the desired glide slope approach angle, with special color filters set between said lamp units and said lens in such a way that a pilot approaching for a landing at too high an altitude will see said virtual images as two clear white lines of light one

above the other, when at correct glide slope altitude will see the top image colored red and the bottom image still clear, when at a position between these altitudes will see the top image pink and the bottom image still clear, when at too low an altitude will see both images colored red and at an intermediate low position will see the top image red and the bottom image pink, with one device set at one side of the runway.

3. An airplane visual landing aid device consisting of an essentially light tight case containing a lens at one end and two lamp units at the other end, each said lamp unit consisting of line filament type lamps arranged horizontally and parallel to said lens and also to the optical axis of the device, one said lamp unit being set above said axis and one below said axis, with apertures between said lamp units and said axis, with mirrors set between said apertures and axis so that two virtual images of said illuminated apertures will appear as lines of light an appreciable distance back of said device, with baffles to prevent light reaching said lens except via said apertures and mirrors, with said optical axis set at an angle to the runway equivalent to the desired glide slope approach angle, with special color filters set between said lamp units and said lens in such a way that a pilot approaching for a landing at too high an altitude will see said virtual images as two clear white lines of light one above the other, when at correct glide slope altitude will see the top image colored red and the bottom image still clear, when at a position between these altitudes will see the top image pink and the bottom image still clear, when at too low an altitude will see both images colored red and at an intermediate low position will see the top image red and the bottom image colored pink, with one device set at one side of the runway.

4. An airplane landing aid device consisting of an essentially light tight case containing a lens at one end and a single lamp unit at the other, said lamp unit consisting of line filament type lamps arranged horizontally and parallel to said lens and to the optical axis of said device, with said lamp unit being set above said axis and with a mirror below said axis and having a relay lens to image said line filament adjacent to said mirror, with baffles to prevent light reaching the lens except from the filament directly and from said second relayed image, said combination being arranged so that two virtual images will appear as lines of light an appreciable distance back of the device, with said optical axis being set at an angle to the runway equivalent to the desired glide slope approach angle, with special color filters set between said lamp unit and lens and between said second lamp image position and lens in such a way that a pilot approaching for a landing at too high an altitude will see said virtual images as two clear white lines of light one above the other, when at correct glide slope altitude will see the top image colored red and the bottom image still clear, when at a position between these altitudes will see the top image colored pink and the bottom image still clear, when at too low an altitude will see both images colored red and at an intermediate low position will see the top image colored red and the bottom image colored pink, with one device set at one side of the runway.

5. An airplane landing aid device consisting of an essentially light tight case having a lens at one end and a line filament type lamp unit at the other end, said lamp unit having line filament type lamps with their filaments set horizontally and parallel to said lamp and at right angles to the optical axis of the device, with said lamp unit being on said axis and having a mirror above said axis and one mirror below said axis, with baffles to prevent light reaching said lens from said lamp unit except via said mirrors, said arrangements being such that two virtual line of light images will be formed a substantial distance back of the device, with said optical axis being set at an angle to the runway equivalent to

the desired glide slope approach angle, with special color filters set between said lamp unit and said lens and set with respect to said mirrors in such a way that a pilot approaching for a landing at too high an altitude will see said virtual images as two clear white lines of light one above the other, when at correct glide slope altitude will see the top image colored red and the bottom images still clear, when at a position between these altitudes will see the top image colored pink and the bottom image still clear, when at too low an altitude will see 10 both images colored red and at an intermediate low altitude

tude will the top image red and the bottom image pink, with one device set one side of a runway.
